UNITED STATES PATENT OFFICE.

JOHN O'LEARY, OF COHOES, NEW YORK.

RAILWAY PASSENGER-CAR.

SPECIFICATION forming part of Letters Patent No. 772,740, dated October 18, 1904.

Application filed March 26, 1904. Serial No. 200,077. (No model.)

To all whom it may concern:

Be it known that I, JOHN O'LEARY, a citizen of the United States, residing at Cohoes, in the county of Albany and State of New York, 5 have invented new and useful Improvements in Railway Passenger-Cars, of which the following is a specification.

This invention relates to railway passenger-cars, and has for its object to provide a car so 10 constructed that it will in appearance and in dimensions possess all the characteristics of the ordinary day-coach and which will be provided with means for converting the same into what is ordinarily known as a "sleeper."

It has for another object to enable the bed-clothing of the sleeper to be aired while the 15 same is not in use without interfering with the ventilation of the car itself.

It further has for its object to provide means 20 for ventilating the upper berth of a car.

It also has for its further object to provide a car seated in the ordinary manner of an ordinary day-coach and means for providing sleeping-apartments, the arrangement being 25 such that separate bed-bottoms will be provided for each occupant of the car aside from any portion of the car that may have been occupied during the day, one of the purposes of this invention being to provide against liability of the occupant of a berth being affected by contagion or infection of a passenger who may have occupied the seat during the 30 day.

In the sleeping-cars as at present in use 35 seats are utilized to form a portion of the beds when they are made up for use at night, and the bedclothing is folded up within what may be termed "pockets" formed in the roof of the car. The objections attendant upon 40 cars so constructed are threefold. In the first place the seats, which are invariably cushioned, have to be used, according to the present arrangement, as mattresses. A bed is made upon these sections, and while the bedding is 45 not in actual use it is sealed up tight against ventilation. By means of this invention the full seating capacity of an ordinary day-coach is maintained, bed-bottoms are furnished for each night passenger, bedclothing is provided 50 for each of said bed-bottoms, and means are

afforded for keeping the bedclothing in a perfectly ventilated and sanitary condition, while at the same time the interior of the car is also ventilated, whereby the comforts of the passengers are preserved without adding to the 55 size of the car. These various advantages are obtained in the manner which will now be described, reference being had to the accompanying drawings, forming a part of this specification, wherein—

Figure 1 is a transverse section taken through one side of the car, the bedding being shown stored. Fig. 2 is a similar view, the berths being shown made up. Fig. 3 is an interior elevation of a portion of one side 60 of the car, showing the lower berth when made up. Fig. 4 is a horizontal section on line 4 4 of Fig. 1. Fig. 5 is a similar section on the line 5 5 of Fig. 1. Fig. 6 is a vertical section on the line 6 6 of Fig. 1. Fig. 7 is a 65 detail perspective view of a portion of one of the posts. Fig. 8 is a detail perspective view of a portion of one of the retaining-plates. Fig. 9 is a detail perspective view of one of the mattress-sections, showing the bedding 70 packed in place. Fig. 10 is a plan view of the same. Fig. 11 is a section taken on the line 11 of Fig. 10. Fig. 12 is an enlarged detailed section taken on the line 12 12 of Fig. 2. Fig. 13 is a detail perspective view 75 of an upper and lower berth bed-bottom nested together, the lower-berth bottom being shown slightly withdrawn. Fig. 14 is a longitudinal sectional view of the same, and Fig. 15 is an enlarged sectional view on the line 15 15 80 of Fig. 2. Fig. 16 is an elevation of the car-seat, and Fig. 17 is a section taken upon the line 17 17 of Fig. 16.

Referring to the drawings, the numeral 1 indicates the floor of the car, 2 the outside 85 sheathing, and 3 the interior lining, the sheathing 2 and 3 extending up to the level of the window-frames, each of said frames being provided with a drip-board 5. Arranged at suitable distances apart are vertical posts 6, 90 which form the vertical side supports of the car. The space between the outer sheathing 2 of the car and the inner lining 3 is utilized 95 to store the bed-bottoms, and at its upper end is closed by hinged lids or covers 6^a, which 100

normally operate to form sills, but are adapted to be raised up to permit of the withdrawal of the bed-bottoms, said sills being hinged to the sides of the car, as at 7.

- 5 Adapted to be seated between the outer sheathing 2 and the interior lining 3 of the cars are bed-bottoms 8 and 9, which are arranged in pairs and are constructed to form the upper and lower sections of the berths. 10 The section 8 consists of a rectangular frame 9^a, the ends of which are extended, as indicated by the numeral 10. The frame is provided with a woven-wire mattress-bottom 11, and said frame at its lower end is provided 15 with fixed pintles 12, and at its upper corners is provided with spring-bolts 13, which normally project beyond the ends of the frame. Said frame is provided at its opposite ends with grooves 14, in the upper ends 20 of which are pivoted the ends of links 15, and said links at their lower ends are pivoted, as at 16, to links 17, which are provided at their free ends with hooks 18. The frame just hereinbefore referred to is designed to constitute the upper berth, and arranged to be nested within said frame is the bed-bottom, which is designed to constitute the lower berth, said frame comprising a rectangular structure 19, adapted to fit between the flanges 25 30 of the frame 9^a, before referred to, and provided with a woven-wire mattress or the like, 20. To the ends of the frame 19 are hinged wings 21, which are adapted to be folded down in parallelism with said frame 35 and to be also turned out at right angles thereto. In practice I attach metallic plates 22 to the ends of the frame 9^a, which plates overlap the grooves 14 and form in conjunction with the grooved portions of the ends of 40 the frame recesses in which the arms 15 and 17 may be folded.

The frame 19, which constitutes a bed-bottom, after its end wings 21 have been folded down in place is adapted to be slid into place 45 alongside of the frame 8, its end rails resting between the end flanges 10 of the frame 8. The two frames thus nested together when not in use are disposed between the sheathing 2 and the lining 3 of the car and are concealed 50 from view by the hinged sill 6^a. Formed on the adjacent sides of the posts 6 are grooves 23, which extend from a point slightly below the hinged sills 6^a to a point at the top of the lower deck of the car-roof. These grooves 55 may be conveniently formed by making rabbets in the sides of the posts, and attached to the edges of the posts are metallic plates 24, which will overlap the rabbeted edges of the posts. The plates are provided at suitable 60 points with offset pockets 25, and each plate is arranged to extend beyond the opposite edges of the post to which it is attached, so as to form a face-plate for the two adjacent berths. As described, the grooves 23 extend 65 up to and slightly above the ceiling of the car

and from thence extend to the dome of the car. Arranged between the posts 6 of the sides of the car are stanchions 26. In practice the arrangement will be such that each pair of posts 6 will embrace between them 70 three car-seats, and between each pair of such posts will be disposed the vertical stanchions 26. Arranged between said stanchions and posts are window-sashes 27 and 28, the windows 27 constituting the ordinary car-windows 75 and the windows 28 forming means for ventilating the upper berths of the car, as will be hereinafter more fully explained.

Arranged in the car after the manner of an ordinary day-coach are a series of seats 80 29, each comprising a supporting-frame 30, a seat-section 31, and a back 32. The seat-section and its supporting-legs may be constructed in any suitable or preferred manner; but to each leg-section 30 of the car is pivoted 85 a lever 32', to the opposite ends of which are pivotally connected links 33 and 34, the opposite ends of said links being pivotally connected to the edges of the backs 32. Arranged on the under side of each seat-section is a 90 manifold bolt comprising two U-shaped yokes 35, the ends 36 of which are adapted to be projected beyond the ends of the seat, said yokes being connected together by pivoted levers 37, the levers 37 forming, in effect, 95 a toggle-joint. The pivot 38 of said levers is made in the form of a thumb-nut, which is adapted to travel in a groove 39, formed in a transverse bar 40, forming a portion of the under side of the seat, the arrangement being such that when the levers 37 are moved into alignment their extremities 36 will be projected beyond the ends of the seat in such manner as to form stops or abutments 100 for the arms 33 and 34 of the seat-backs. It 105 will be noticed that the lower edges of the seat-backs rest upon the edges of the car-seats and that the distance between the projecting ends 36 of the bolts is such as will permit of the seat-backs being reversed, the levers 32' during such operation turning between the extended ends 36 of the bolts. By unscrewing 110 the thumb-nuts 38, however, and breaking the joint between the levers 37 the ends 36 of the bolts are retracted and the back of the 115 seat may then be lowered until one of its edges rests upon the floor of the car, and owing to the fact that the backs are permitted to assume an inclined position their upper edges will then rest flush with or slightly below the level of the car-seats. Supports are thus provided for the lower-berth bed-bottoms 120 19. In making up the berths the bed-bottom 19 is withdrawn from the side of the car and is placed upon three of the car-seats, the backs of which have been previously lowered in the manner described. The corresponding bed-bottom 8 is then raised in its groove, the pintles 12 and 13 traveling in the 125 grooves as it is elevated, and when it has been 130

elevated to the proper distance the spring-bolts 13 are retracted. At this moment the pintle 12 will be opposite the pockets 25, and by drawing down the free end of the bed-section 5 the pintles 12 will be drawn to their seats within said pockets. The hooked ends 18 of the arms 17 are then hooked over suitable projections 41 in the top of the car, whereby the upper-berth section is supported in a horizontal position. Each sleeping-section of the car will thus be provided with a mattress-section that is entirely independent of the ordinary fittings of the car—that is to say, heretofore the seats of sleeping-cars have been 10 utilized to form portions of the lower berths, whereas in my invention I am enabled to provide a berth wherein the occupant is not compelled to rest upon the seats which for hours before may have been occupied by some other 15 person.

In sleeping-cars as heretofore constructed it has been necessary to arrange the car-seats at such distances apart as to support a berth-section between each two adjacent seats, or, 20 on the other hand, to make the backs of the seats themselves portions of the lower berth. By the construction I have before described I am enabled to arrange the seats precisely in the manner that they are ordinarily arranged 25 in the ordinary day passenger-coach and to dispose them at the same distances apart and at the same time I am enabled to avoid the use of any part of the seat which has been occupied during the day to form a portion of 30 the berth for a passenger at night.

In practice the bed-bottoms are provided with bails or handles by means of which they may be raised from their receptacles in the sides of the car, and, preferably, a pulley 43 is 35 attached to the framework of the lower deck of the car, about which pulley passes a cord 44, provided at one end with a hook 45. The hook 45 may be engaged with the bail or handle 42 of either one of the sections, and by pulling 40 upon the cord 44 the bed-section may be raised from its receptacle in the side of the car into operative position, after which the hook 45 may be disengaged and may be caused 45 to engage the adjacent or corresponding bed-section, after which the cord may be employed to raise said second bed-section into operative 50 position.

Formed between the ceiling of the car and the lower deck thereof on each side of the dome 55 is a space 46, which is utilized to contain the mattresses and bedclothing, and formed in the ribs, which are arranged at the ends of said spaces, are grooves 47, which extend from the dome of the car to the lower edge of the ceiling, said grooves terminating at their lower 60 ends in pockets 48. The bedclothing for the two berths of each section is carried by a frame (indicated in a general manner by the numeral 49) comprising a rectangular frame 65 50, preferably constructed of wood and pro-

vided at its lower ends with fixed laterally-projecting pintles 51 and at its upper corners with spring-bolts 52, which also serve the purpose of pintles. The sides of the frame 50 are provided on their upper and lower sections with buttons 53. Carried by the frame 50 are two mattresses 54 and 55, said mattresses being detachably connected to the frame 50 by flexible straps 56, which are sewed to the mattresses and are arranged to 70 be buttoned to the buttons 53. The lowermost mattress 55 is provided with pockets 56^a, which are arranged to contain the pillows for the two berths. Attached to the ends of the frame 50 are strips 57, to which are hinged 80 wings 58, the arrangement being such that when the mattresses and bedding are attached to the frame said wings may be folded flat thereon. Each of the wings is provided with a pivoted hook 59 at its upper inner corner, 85 as shown. A strap 60, composed of textile material, is connected at one edge of the frame 50 intermediate the ends of the latter, and after the mattresses have been secured in place in the manner described and the wings 58 have 90 been folded down said strap is passed over the frame, embracing the ends of the two wings, and is then buttoned to a button 61 on the opposite edge of the frame. Each of the frames 50 is provided on one edge with a bail or handle 95 62, which is adapted to be engaged by a hook 63, attached to one end of a cord 64, which passes over a pulley 65, attached to the side of the dome immediately beneath the upper deck. The frame 50, carrying the mattresses and 100 bedding is designed to repose in the chamber 46, formed between the ceiling and the roof of the car, and when the parts have been folded and secured together in the manner described said frame may be slid vertically upward in the grooves 23 and thence inwardly in the grooves 47, a hinged door 66 being formed in the ceiling to permit of the said frame being pushed into place. Arranged in the upper end of the chamber 46 is a bent leaf-spring 105 67, and when the frame 50, containing the mattresses and bedding, is pulled up into the chamber 46 by the cord 64 its upper edge will engage the spring 67. Then by slightly raising the lower edge of the frame and releasing the cord the pintles 51 drop into the pockets 48, whereby the frame is held in place. Arranged in the vertical side connecting the upper and lower deck portions of the roof are 110 transoms 68, which are hinged at their upper ends, as at 69, and connected to each of said transoms is a bent lever 70, which is pivoted at a point, such as 71, to a link 72, which is pivoted to the side of the car-roof at its other end, the arrangement being such that as the 115 bent-lever 70 is pushed up the transom is swung upward and outward. This permits of a free circulation of air in the chamber 46, containing the bedclothing, whereby the latter is thoroughly ventilated when the bed- 120 125 130

ding is not in use. In order to prevent the access of soot, dirt, and the like to the bedding, screens 73 are provided, which are hinged at their upper edges to the eaves of the car-roof and are fastened in place at their lower edges by means of catches 74. A pan 75 extends from the level of the transom-opening toward the dome of the car and at its inner edge is provided with an upturned flange 76, and extending from said flange to the frame above the transom-opening is a fine screen 77. From time to time, as it becomes necessary, the screens 77 may be raised and the transoms 68 opened, after which any soot, cinders, or the like which may have accumulated in the pan 75 may be readily removed from the outside of the car. Arranged in the dome of the car at one side of the chamber 46 are transoms 78, which are pivoted intermediate their ends and centrally between their tops and bottoms, as at 79. By opening these transoms the interior of the car may be ventilated. Curtain-poles 80 are fixed in suitable brackets 81 along the edges of the dome of the car in a usual manner and are arranged to support curtains 82 to close the berth-sections. During the day when the berths are not in use said curtains are rolled up and are stored in the chamber 46, suitable straps 83 being provided to pass around the rolled curtains and are buttoned to buttons 84, by means of which the curtains are stored away. Preferably beveled blocks 85 are attached to the inner lining 3 of the car at the bottom of the receptacles arranged to contain the bed-bottoms which are adapted to be engaged by the pintles 12 of the upper-berth sections when the latter are lowered into place, and sockets 86 are formed in the upper portion of the said chambers which are adapted to be engaged by the pintles 13 in the manner which will presently be described.

It will be noted that by means of my invention I am enabled to dispense with the cupboards formed in the ceilings of the cars on each side of the dome such as are in common use at the present day and that I am also enabled to provide storage-room for the bed-sections and bedding without increasing the height or the width of the ordinary day-coach. In fact, when the parts are stored away there is no difference whatsoever in the dimensions, appearance, or seating capacity of the ordinary day-coach. When it becomes necessary to convert the car from a day-coach to a sleeper, the seat-backs 32 are thrown down into their inclined positions by means of loosening the thumb-screws 38 and breaking the joints between the levers 37, whereby the ends 36 of the bolts are retracted to permit of the seat-backs being lowered, so that each of said backs will rest upon the bottom of the car, and owing to their inclined positions what constitutes the upper edges of the

backs will lie in the same horizontal plane 65 with or below the planes of the car-seats.

A description of the operation of one section will suffice for that of the entire car and is as follows: After the seat-backs have been folded down upon the floor of the car in the manner described the hinged sills 6^a are folded back and the hook 45, attached to the cord 44, is connected to the handle on the corresponding berth bed-bottom 19 and the latter is hoisted out of the chamber in the side of the car and is placed upon the adjacent three seats. The hook 45 is then detached and is connected to the handle 42 of the corresponding upper-berth section 8 and the latter hoisted, its pintles riding in the grooves 23. After the upper-berth section has been elevated a suitable distance its lower edge is drawn inward toward the aisle of the car, causing its pintles 12 to seat themselves within the pockets 25. Then by releasing the cord the bed-bottom is permitted to drop, and by unfolding the arms 15 and 17 and hooking the ends 18 of the arms 17 to their supports the berth is held in a horizontal position. The panels 66 having been opened, it is only necessary to draw upon the cords 64, when the frame carrying the mattresses and bedding will be raised sufficiently to cause their pintles 51 to unseat themselves from their sockets 48, and the pintles will then slide down the grooves 23, permitting the bedding-frames to drop vertically. The upper-berth sections having been lowered into position in the manner before described, their edges adjacent to the exterior of the car will form bottoms against which the lower edges of the bedding-frames will strike when they are lowered from the compartments in the roof. Then by retracting the spring-bolts 52 said frames may be lowered onto the upper berths. Before doing this, however, the mattresses, which are buttoned to the lower sides of the bedding-frames, are detached from the frames and placed upon the bed-bottoms of the lower-berth sections, and the pillows are removed from their pockets and placed in position. The usual pockets for containing the bed-lining and the like are provided, and from the same the bedding is removed and applied to the berths. As before described, each one of the lower-berth bed-bottoms is provided with end wings 21, and when these bed-bottoms are placed in position upon the seats the said frames are turned to a vertical position. Attached to each one of said wings is a pivoted button 87, and formed on the frames 9^a, in proximity to the spring-bolts 13, are grooves 88, the arrangement being such that after the upper and lower berth bed-bottoms have been moved into place to make up the berths and the end wings having been raised to a vertical position the buttons 87 will be turned so as to engage the grooves 88 and hold the end wings in position to form

partitions between the berth-sections. As has been before described, the bedding-frame is provided with end wings 58, and after the latter have been placed in position upon the 5 upper-berth bed-bottom said wings are raised and by means of the hooks 59 are secured in place, thus completing the partitions between the upper-berth sections. The berths are now complete, and an occupant of a lower 10 berth by raising or lowering the windows 27 may ventilate his berth to satisfy himself, and the occupant of the upper berth may in like manner, by raising or lowering the windows 28, ventilate his berth. When it becomes 15 necessary to convert the car into a day-coach, the mattresses and bedding are rebuttoned and strapped to their frames and are hauled, by means of the cords 64, back into their receptacles 46, formed between the ceiling and the 20 roof of the car, the panels 66 having first been opened. As each bedding-frame is raised into position in the said chamber its lower edge is slightly raised by hand in the manner before described and its elevating-cord released, whereby the pintles are forced back 25 into the seats 28, securely holding the frames in place. The upper and lower berth bed-bottoms are then nested together and drop into the chamber between the inner lining and 30 outer sheathing of the car, and as they drop into place the pintles 12 will strike against the guide-blocks 85, whereby said bed-bottoms will be laterally moved over against the outer side of the car, the pintles 13 at the 35 same time riding into the sockets 86, whereby the bed-bottoms will be securely held in place within their receptacles in such manner that they cannot vibrate or rattle. The sills 6^a are then closed, and the seat-backs are re- 40 stored to their normal position and the bolts shot forward to lock them into place, it being of course understood that the panels 66 have been closed. The car is thus restored, to all practical purposes, to an ordinary day- 45 coach.

Having described my invention, what I claim is—

1. In a passenger-car, berth bed-bottoms removably stored between the outer sheathing 50 and inner lining of the car, one of said berth bed-bottoms being removably carried by the other, and means for withdrawing said bottoms from their compartments.

2. In a passenger-car, berth bed-bottoms 55 nested together and removably stored between the outer sheathing and inner lining of the car, and means for separately withdrawing said bed-bottoms.

3. In a passenger-car, berth bed-bottoms 60 nested together and removably stored between the outer sheathing and inner lining of the car, said bed-bottoms being provided with bails upon their upper edges, and a cord and pulley, one end of said cord being provided with a 65 hook which is adapted to be detachably con-

nected with either of said bails, whereby the two bed-bottoms may be independently hoisted from their compartment.

4. In a passenger-car, the combination of 70 berth bed-bottoms removably stored between the outer sheathing and inner lining of the car, means for withdrawing said bed-bottoms from their compartments, and means for holding said bed-bottoms against movement when lowered into their compartments, for the purpose specified. 75

5. In a passenger-car, the combination with 80 a hinged sill arranged to cover the space between the outer sheathing and inner lining of the car, of bed-bottoms normally disposed between said sheathing and inner lining, means for tightly holding said bottoms against the outer framework of the car, and means for withdrawing said bed-bottoms, substantially as described. 85

6. In a passenger-car, the combination with 90 two bed-frames each provided with a woven-wire bottom, one of said frames being provided at its ends with flanges, whereby the other frame is adapted to be nested in said first frame, said frames being normally stored between the outer sheathing and inner lining of the car, and means for withdrawing said frames from their receptacles, substantially as described. 95

7. In a passenger-car, the combination with 100 a bed-bottom arranged to be stored between the outer sheathing and inner lining of the car, said bottom being provided at its lower ends with fixed pintles and at its upper ends with retractile pintles, said pintles being arranged to travel in grooves formed in the posts of the car between which the bed-bottoms are disposed, whereby, after the bed-bottom has been elevated, the retractile pintles may be withdrawn and the bed-section lowered into place. 105

8. In a passenger-car, the combination with 110 a car provided on its sides at suitable distances apart with grooved posts provided with laterally-projecting pockets, of a berth bed-bottom normally disposed between the outer sheathing and inner lining of the car, and means for raising said bed-bottom from its compartment, said bed-bottom being provided 115 at its opposite lower ends with projecting pintles which are arranged to be seated within said pockets, substantially as described.

9. In a passenger-car, the combination with 120 the car provided at suitable intervals with vertical posts vertically grooved and provided with interiorly and laterally extending pockets, of bed-bottoms normally stored between the outer sheathing and inner lining of the car and having connected to their opposite 125 ends folding arms the free ends of which are provided with hooks, means for raising said bed-sections from their compartments, whereby they may be folded toward the interior of the car, and projections in the top of the car 130

that are adapted to be engaged by the hooks to hold the bed-bottoms in a horizontal position, substantially as described.

10. In a passenger-car, the combination of 5 posts arranged at suitable distances apart on the sides of the car and vertically grooved on their edges, of bed-bottoms removably stored between the outer sheathing and inner lining of the car and provided with pintles arranged 10 to travel in said grooves, means for withdrawing said bed-bottoms from their compartments, and means for supporting the said bottoms in a horizontal position, for the purpose specified.

15. 11. In a passenger-car, the combination with a series of posts arranged on the sides of the car and provided with vertical grooves, of bed-bottoms removably stored between the outer sheathing and inner lining of the car and 20 provided with pintles which are adapted to travel within said grooves, the ends of said bed-bottoms being grooved, folding arms attached to the bed-bottoms and arranged to fold within said grooves, the free ends of said arms 25 being provided with hooks, and projections attached to the upper part of the car, the arrangement being such that when the bed-bottoms are withdrawn from their compartments and lowered to a horizontal position said 30 hooked ends may be caused to engage said projections and hold the bed-bottoms in place, substantially as described.

12. In a passenger-car, the combination with a series of vertically-grooved posts arranged 35 at suitable distances apart, of bed-bottoms removably stored between the outer sheathing and inner lining of the car between said posts, said bed-bottoms being provided at their lower ends with fixed pintles and at their upper 40 ends with retractile pintles which are adapted to travel in said grooves and also provided at their opposite ends with hinged wings which, when the bed-bottoms are lowered to a horizontal position, are adapted to be turned 45 vertically and form partitions between the berth-sections, substantially as described.

13. In a passenger-car, the combination with two bed-bottoms arranged to form the bottoms of the upper and lower berths, each of 50 said bottoms comprising a rectangular frame having attached thereto a woven-wire mattress, one of said frames being provided at its ends with right-angular projections between which the outer frame is arranged to 55 slide, substantially as described.

14. A passenger-car provided with a chamber between the ceiling and the roof, in combination with frames having attached thereto mattresses for the berths, and means for raising and lowering said mattress-frames into 60 and out of said compartments, substantially as described.

15. In a passenger-car, the combination with the car provided with chambers between its 65 ceiling and its roof for the reception of mat-

tress-frames, of means for raising and lowering said mattress-frames into and out of said compartments, and means for ventilating said compartments, substantially as described.

16. In a passenger-car constructed to receive the berth-bedding between the ceiling and the roof of the car, suitably-mounted transoms arranged between the upper and lower decks of the car-roof, pans arranged next to the interior of the transoms, and screens extending from the upper edges of said pans to the sides of the car, substantially as described. 70 75

17. In a passenger-car constructed to receive the berth-bedding between the ceiling and the roof of the car, of hinged transoms arranged between the upper and lower decks of the car-roof, means for opening and closing said transoms, pans arranged next to the interior of the transoms, and wire screens 80 85 extending from the upper edges of said pans to the sides of the car, substantially as described.

18. The combination in a passenger-car provided with a chamber between the ceiling and the roof thereof, of frames having attached thereto mattresses for the berths, said chamber being constructed to receive the mattress-frame and bedding when not in use, and straps fixed in said chamber for holding the berth-curtains when not in use, substantially as described. 90 95

19. The combination in a passenger-car provided with a chamber between the ceiling and the roof thereof, of frames having attached thereto mattresses for the berths, said chamber being constructed to receive the mattress-frame and bedding when not in use, and a hinged panel arranged in the ceiling, substantially as described. 100 105

20. The combination in a passenger-car provided with a chamber between the ceiling and the roof thereof, of frames having attached thereto mattresses for the berths, straps for holding the bedding in place when not in use, and means for raising and lowering said mattress-frames into and out of said chamber, substantially as described. 110

21. The combination in a passenger-car provided with a chamber between the ceiling and the roof thereof, of frames having detachably-attached mattresses for the berths and provided at its ends with folding end wings, said wings being adapted to fold down upon the bedding when the latter is not in use, and straps for holding the wings and bedding in place when folded down. 115 120

22. The combination in a passenger-car provided with a chamber between the ceiling and the roof thereof, of frames having attached thereto mattresses for the berths, said mattresses being buttoned to the frames and provided with pockets for holding the pillows, substantially as described. 125

23. The combination in a passenger-car pro- 130

vided with a chamber between the ceiling and the roof thereof, of frames having attached thereto mattresses for the berths, means for raising and lowering said mattress-frames into and out of said chamber, a compressible spring arranged in the upper end of the chamber, a socket arranged in the lower end thereof, the whole being constructed and arranged whereby, when a mattress-frame is raised up into said chamber, it will abut said spring and the latter will operate to force the opposite ends of the mattress - frame into said socket and hold the frame in place.

24. The combination in a passenger-car provided with a chamber between the ceiling and

the roof thereof, of frames having attached thereto mattresses for the berths, means for raising and lowering said mattress - frames into and out of said chamber, and pintles formed on the ends of said frames and arranged to travel in grooves in the sides of said chamber and the side of the car, substantially as described.

In testimony whereof I have hereunto set my hand in presence of two subscribing witnesses.

JOHN O'LEARY.
